STRAIGHT-BAR KNITTING MACHINE

Harry Wilfred Start, Carlton, and Ernest Start,
Wilford, England, assignors to George Black-
burn and Sons Limited, Nottingham, England

Application June 19, 1941, Serial No. 398,818
In Great Britain April 23, 1940

5 Claims. (Cl. 66—90)

This invention relates to improvements in straight-bar knitting machines and relates to machines provided for knitting tabs to a part of a garment such as the heel tabs which are knitted to a blank comprising the leg and foot portion of a stocking and which are provided with two groups of needles and with knocking-over bits which are carried by a bar disposed in front of the needle bar.

In order to knit the heel tabs to the blank the latter is first run on the needles whilst the latter are withdrawn from their operative position and the foot portion is disposed on the front or bearded side of the needles and hangs down over the knocking-over bits whilst the leg portion is disposed on the rear side of the needles. The needles are then moved into their operative position and the first course drawn on the two sets of needles and the needles then moved into their lowermost position. Whilst the needles are in this position that portion of the blank which is disposed on the front of the needles is withdrawn onto the rear side of the needles.

The needles are then raised and knitting of the heel tabs continued in the usual manner.

It will be understood that when the blank is placed in position on the needles the foot portion of the blank extends across from one set of needles to the other and hangs down over the knocking-over bits and behind the needle bar. When this part of the blank is withdrawn onto the rear side of the needles the latter are in their lowest position and the beards of the needles extends down below the undersides of the knocking over bits. As the knocking-over bits are carried from a bar disposed in front of the needle bar there is nothing to prevent the blank catching on the beards of the needles disposed on the inner sides of the two groups when the foot portion is withdrawn onto the rear sides of the needles. This is a disadvantage as the blank frequently catches on the beards when it is being withdrawn and apart from the fact that it may damage the needles or the blank, time is lost in getting it free again.

The object of the present invention is to prevent the blank catching on the needles and so obviate damage or loss of time.

According to this invention a guard is secured on the knocking-over bar and extends rearwardly and downwardly between the two groups of needles to hold that part of the blank which is disposed on the front of the needles clear of the latter.

The invention will now be more particularly

described with reference to the accompanying drawing in which:

- Fig. 1 is a front elevation and
Fig. 2 a plan of a knocking-over bar fitted with
5 a guard according to our invention,
Fig. 3 is a section on the line XX of Fig. 2 and
Fig. 4 is a section of a knocking-over bar showing
the needles in their lowermost position after
drawing the first course through the blank.
- 10 Like letters indicate like parts throughout the
drawing.
- In carrying out this invention the guard A is secured to the knocking-over bar B and ex-
tends the full distance between the two groups
15 of knocking-over bits B¹, B² carried by the bar. The guard is provided with an extension C or
with lugs and is secured by this extension or
the lugs to the knocking-over bar B and when
in position extends towards the rear of the ma-
chine and passes between the two groups of
20 needles when the latter and the knocking-over
bits are in their operative positions. The guard
passes between the needles at approximately the
same level as the tops of the knocking-over bits
25 B¹, B² and is then turned downwardly so that the
rear edge A¹ of the guard extends some little
distance past the needles and below the points
of the beards when the needles are in their low-
est position as shown in Fig. 4.
- 30 The sinker sley provided in machines of this
type is cut away between the two groups of sink-
ers to provide clearance for the guard.
- The guard may be formed from a casting or a
35 plate of suitable thickness bent to the required
shape. The ends of the guard may be made
higher than the middle to further assist in hold-
ing the blank D (see Fig. 4) clear of the needle
beards when it is being withdrawn by the op-
erator of the machine.
- 40 When a machine for the purpose described is
fitted with a guard as described there is no like-
lihood of the blank catching on the beards of the
needles when being withdrawn from the front of
45 the needles to the rear and the guard also forms
a support on the underside of the blank and en-
ables the operator to more readily obtain a hold
on the blank in order to withdraw it.
- What we claim as our invention is:
- 50 1. In a straight-bar knitting machine of the
kind described the combination with the knock-
ing-over bar of a guard disposed between the two
groups of knocking-over bits to prevent the work
extending in front of the needles during the
formation of the first course catching on the

needle beards when it is withdrawn onto the rear side of the needles substantially as described.

2. In a straight-bar knitting machine of the kind described the combination with the knocking-over bar of a guard secured thereto and extending across between the two groups of knocking-over bits and rearwardly and downwardly between the needles when the latter and the knocking-over bar are in operative position substantially as described.

3. In a straight-bar knitting machine of the kind described the combination with the knocking-over bar of a guard which extends across between the two groups of knocking-over bits and passes between the needles at approximately the same level as the tops of the knocking-over bits and extends down to a point below the points of the needle beards when the needles are in their lowest position substantially as described.

4. In a straight-bar knitting machine of the kind described the combination with the knocking-over bar of a guard disposed between the two

groups of knocking-over bits and having sides which pass between the needles at approximately the same level as the tops of the knocking-over bits a centre disposed at a lower level than the sides and a rear edge which extends down below the points of the needle beards when the latter are in their lowest position substantially as described.

5. In a straight-bar knitting machine of the kind described the combination with the knocking-over bar of a guard comprising a frame disposed between the two groups of knocking-over bits and having a front edge secured to the knocking-over bar, sides passing between the needles at a point approximately level with the tops of the knocking-over bits and a rear edge which extends down below the points of the needles beards when the needles are in their lowest position.
